METHOD OF STEAMING FABRICS

William J. Koch, Midland Park, N. J., assignor
to Van Vlaanderen Machine Company, Pater-
son, N. J., a corporation of New Jersey

Application April 15, 1935, Serial No. 16,416

6 Claims. (Cl. 38—152)

In what are known in the art of steaming fibrous fabrics as "decating" machines the fabric is wound with a blanket or "mantle" on a peripherally perforated hollow drum, both the fabric and 5 blanket being of coarse fluid-pervious; steam is admitted to the drum and hence to the wound mass; then, the steam being cut off, vacuum is applied to the drum to cause atmospheric air to be drawn through the mass in the effort to 10 remove the condensate therefrom or so far as possible dry the fabric and blanket and also cool them; and finally the fabric and blanket are unwound from the drum and wound on respective receiving elements therefor, as beams. When 15 this treatment is repeatedly performed, as on a succession of fabrics, the blanket (which is usually about $\frac{1}{2}$ inch thick) becomes in time so heavily laden with moisture of condensation that notwithstanding the vacuum action the treatments cannot follow each other in the practically 20 uninterrupted succession which means the maximum possible output without likelihood of moisture retained in the blanket harming the product, to wit, when each freshly introduced fabric is wound up with the blanket on the drum preparatory 25 to steaming. In short, if it is desired to treat fabrics one after another without loss of time the operator must at present accept the hazard that the fabrics will be harmed.

In practice, of the whole time devoted to each 30 fabric only approximately one-third is taken up with the actual steaming and vacuumizing, the remaining two-thirds interval being occupied in loading, or forming the wound fabric-and-blanket mass, on the drum, removing the fabric and blanket from the drum after the steaming and vacuumizing and winding them on their receiving beams or equivalent elements, removing the beam wound with the treated fabric, and placing 35 in the machine a beam wound with the next fabric to be treated.

It has been proposed to dry the blanket by 40 merely causing it to travel past a heating medium, as when it is being wound up with the blanket 45 onto the drum. But, since the blanket in time becomes quite thoroughly saturated with the moisture, an actually effective drying in this way, or with mere heat and progressively with respect to a travelling stretch of the blanket, requires the speed of the blanket to be so slow that 50 in point of time and hence of output there is actually a great loss; truly effective economy in these respects means that the blanket should travel at its highest practicable speed, and if this 55 is done then, once well moistened, it remains con-

tinually moistened notwithstanding any effort to dry it in this way.

According to this invention a complete drying can in practice be effected after each steaming because the drying is effected by resort to vacuum and with respect to the blanket as it exists in a wound mass on its receiving element and in a time-interval which is adequate for such complete drying, to wit, within that interval which may begin as late as when the blanket and one fabric have been unwound from the drum and which may end when the blanket and next fabric have been completely wound on the drum preparatory to the steaming and vacuumizing thereof.

In these machines, as regards the drum and blanket-receiving element, when the winding of either with the blanket is checked it is desirable to brake the other so that the latter will not overrun and cause undue slack in the blanket, 20 wherefore the invention further contemplates novel means for effecting the winding motion of either and the braking of the other of these elements.

In the drawings, 25
Fig. 1 is a side elevation of a machine embodying and by which this invention is performed;

Fig. 2 is a fragmentary longitudinal section of the drum 2 thereof;

Fig. 3 is a similar view of the drum 18 with the axial core thereof in elevation;

Fig. 4 is an elevation, as seen in Fig. 1 and on a larger scale, of the means for effecting the winding and braking of the drums, upper and lower portions appearing in partial section in vertical planes respectively through an upper slot 50 and a lower slot 46a of the slide 46;

Fig. 5 is a vertical longitudinal substantially central section of what is shown in Fig. 4; and

Fig. 6 is an elevation of said slide 46. 40

In the frame 1 is journaled the mentioned drum 2 on which a fabric and the blanket are wound for the steaming, one of its bearing trunnions 3 being tubular. The drum has the usual construction, to wit: Its cylindrical wall is circumferentially foraminous, here perforated (indicated only in Fig. 2 and in one diameter) and the perforations are fitted with inwardly projecting tubes 4 having their inner ends bent off so that condensation accumulating in the drum shall not escape at the perforations happening to be at the bottom. It contains an axial tubular perforated core 5. Its end shown in Fig. 2 is enlarged to form an interior circumferential channel 6, and in this channel are arranged the enlarged mouths 50 55

or buckets 7 of curved water conductors 8 merging together in an axial tube 9, the buckets being all open in the direction the same as that in which the drum rotates to deliver the wound mass formed thereon. Steam from a pipe 10, discharging into the connection 11, in turn discharging into core 5 and filling the drum, will escape via the tubes 4 and hence through the wound fabric-and-blanket mass to the atmosphere, any condensation forming and collecting at the bottom being prevented from reaching such mass by the tubes; when the steaming of said mass has been effected vacuum applied to connection 11, as by a pump 12 (driven by an electric motor 13), whose suction side is connected with said connection by a pipe 14 and its branch 14a will cause atmospheric air to be drawn through said mass and the drum, and in the unwinding of the mass from the drum such condensation as tends to collect, finding its way to the channel 6, is taken up by the buckets and discharged by pipe 8 into said connection and hence toward the pump.

The fabric *a* comes to the machine wound on a beam 15 whose trunnions are supported in suitable bearings 16 of the frame 1. When, with the blanket *b*, it is wound on the drum it extends trained around suitable guides 17 and then, with the blanket, between a nip roller 17a and the drum. The blanket, *b*, extends from its rotary receiving element or a smaller drum 18 journaled in the frame around a guide 19 and a set of guides 20 and between the nip roller and the fabric. When the unwinding of the wound mass on the drum 2 is effected an empty beam, as 21, has its trunnions made to rest on arms 22, which are swung up to the inclined position shown in Fig. 1 for this purpose, and rests itself against the rotating nip roller 17a, being frictionally rotated thereby.

Now according to my invention the smaller drum 18 (see Fig. 3) is hollow and formed circumferentially foraminous, here with perforations 18a (indicated in only one diameter and partially in this figure), and it has a tubular core or axial portion 18b which is likewise perforated, the end of such core protruding. Said core has its protruding end connected (as by a suitable gland, not shown) with a branch 14b of pipe 14, the juncture of the branches 14a and 14b and such pipe being a valve-chamber 23 containing a three-way valve 24 whose three ports are shown dotted in Fig. 1 at 24a. The stem of the valve has an arm which is connected by a link 25 with a lever 26 fulcrumed on an extension 23a of the valve chamber. In the position of the lever shown the pump is maintaining a vacuum in drum 2, drum 18 being cut off from the pump; movement of the lever to the left (dotted position) will cause the pump to maintain the vacuum in drum 18, drum 2 being cut off.

The operations are as follows: A beam 15 being placed in the machine and the free end of the fabric, wound thereon, placed between the drum 2 and the blanket (wound on drum 18 and left partially wound on drum 2), said drum 2 is driven to wind the fabric and blanket thereon. When the winding is completed steam is first admitted to said drum and hence passes through the fabric-and-blanket mass; then the steam is cut off and the lever 26 (which was maintaining the valve 24 in position to cause the vacuum to be active on drum 18) is shifted to the right to cause the vacuum to be active on drum 2 and hence on said mass, the flow of atmospheric air through the mass ridding it of moisture and cooling the

mass. Drum 18 being now rotated to wind the blanket thereon, the fabric is wound on the beam 21 due to the rotation of drum 2 incident to the pull of the blanket. Valve 24 may remain in its last-named position during this step in the operation or in fact until such unwinding has been completed, but usually by the time such unwinding has been completed it is shifted to the position for maintaining the vacuum on drum 18 and the wound blanket mass thereon and retained in that position until a fresh fabric, wound on a beam such as 15, has been placed in the machine and the re-winding of it and the blanket on the drum and the ensuing steaming have been effected. In any event, since the steaming step is one requiring in practice not more than one-third of the whole time devoted to the sequence of operations beginning with the incorporation of a fabric in the machine and ending when the incorporation of the next fabric to be treated ensues, the remaining time interval is more than ample in the case of a blanket of the average thickness and compactness to effect its drying to such a degree that all danger of harming the fabric is completely avoided.

It should be borne in mind that what is ultimately sought by this invention is an increased output of fabrics treated without the incident of injury to the fabrics due to moisture retained in the blanket. Factors in the obtaining of these results by this invention are that the moisture in the blanket is actually dislodged by application of a vacuum to the blanket and rather to it when in the form of a wound mass than to it when travelling past a drying medium, as a vacuum source, so that such mass in situ is subjected to the drying action and the desired speed can be maintained as is not possible when a mere stretch of the blanket travels past a drying medium.

In those instances where the blanket may possibly be unusually thick or compact in texture the drum 18 may be housed in a chamber 27 having an opening 27a through which the blanket may travel and containing a steam coil 28 connected to the steam pipe 10 by a pipe 29. In such case, the wound blanket mass exists in a heated body of atmospheric air and such heated air is drawn through the mass.

The prime mover for the drums is here an electric motor 30. A housing 31 adjoins the motor and contains the following mechanism: Journaled in the housing is a shaft 32 having a gear 33 fixed thereon. Parallel with this shaft and journaled in the housing is a shaft 34 having a gear 35 free to rotate thereon. Alined with shaft 32 is a shaft 36, journaled in the housing and in gear 33. As for the unit (Figs. 4 and 5) now referred to the train comprising parts 32-33 and 35 may be regarded as its rotary input means and the parts 36 and 34 as distinct output means thereof respectively adapted to be driven by part 32-33 and part 35 of the input means; shaft 32 may be connected in any way (not shown) with the motor shaft, as directly, whereas shafts 34 and 36 have sprocket-and-chain or equivalent connections 37 and 38 (Fig. 1) respectively with the drums 2 and 18. Output means 34 is adapted to be driven from its input means by a friction driving clutch 39 splined on shaft 34 and adapted to frictionally grip the gear 35 when a sleeve 40 on shaft 34 is shifted to the right. Output means 36 is similarly adapted to be driven from its input means by a friction driving clutch 41 splined on shaft 36 and adapted to frictionally grip the gear 33 when a sleeve 42

on shaft 36 is shifted to the right. Further, either output means may be braked as follows, to wit, output means 34 by a friction brake clutch 43 splined thereon when the sleeve 40 is moved to the left to cause said clutch frictionally to grip the wall 31a of the housing, and output means 36 by a friction brake clutch 44 splined thereon when the sleeve 42 is moved to the left to cause said clutch frictionally to grip said housing wall.

The purpose of the unit last described, it is in order here to say, is to prevent overrunning of that drum which is being pulled around by the other drum (acting through the blanket) when the rotation of the latter drum is checked. Incidentally, the brake shown at 45 in Fig. 1 is present to preserve tension on the blanket and hence compress the fabric between the windings or layers of the blanket when drum 2 is being loaded.

The shifting of the two sleeves is effected as follows: A plate 46, forming a slide, has straight vertical slots 46a receiving headed studs 47 projecting from bosses on the wall 31b of the housing, the slide being held in wiping contact with said bosses by the heads 47a of the studs. An arcuate yoke 48, embracing each sleeve 40 and 42 and pivoted at 49, has studs 48a engaged in the peripheral groove shown in each such sleeve 30 and also a stud 48b engaged in a slot 50 of the slide. (As noted, portions of Fig. 4 are shown in section in vertical planes coincident respectively with the upper and lower slots 50 and 46a.) The slide may be shifted down or up by a controlling lever suitably fulcrumed in the frame and comprising a shaft 51, a crank 52 thereon within the housing and having a slot-and-pin connection 52a with the slide, and handles 53. The slots 50 are reverse counterparts 40 of each other. From their mid-points x (Fig. 6) their relatively outer end portions 50a extend first straight and vertically and then bent off, their outer terminals being both in the same vertical line at one side of the vertical line of 45 mid-points x; from said mid-points x their relatively inner end portions 50b are bent, the apices of their bends being both in a vertical line at the opposite side of the vertical line of said mid-points and their terminals in the line of said 50 mid-points.

When the controlling lever and hence the slide are in mid-position the mid-points x coincide with the studs 48b, wherefore the sleeves are in mid-position and both friction and brake 55 clutches are inactive. Movement of the lever to shift the slide down will set the driving clutch 39 (thus to drive shaft 34) and incidentally cause brake clutch 44 to temporarily brake shaft 36 and be then retracted; and movement of the 60 lever to shift the slide up will set the driving clutch 41 (thus to drive shaft 36) and incidentally cause brake clutch 43 to be temporarily positioned to brake shaft 34 and then retracted. Movement of the lever to shift the slide back to 65 neutral position will in each case release the drive clutch which had been active and incidentally set the other or non-corresponding brake clutch temporarily and release the same. The setting of a brake clutch when the controlling lever is 70 moved from neutral position has here no especial significance, since both drums are already at standstill; but the setting of a brake clutch when the controlling lever is moved to neutral position has this effect that, upon the power being 75 cut off from the drum last driven by the mo-

tor when the lever is so moved, a braking resistance is applied to the other drum, preventing it from overrunning and hence a slack being developed in the blanket.

Considering the mechanism with respect to 5 the travel of the blanket in either direction, essentially it may be defined as including the following: A driven system itself including a pair of rotary elements (2 and 18) and a flexible connection (b) connecting them and wound on one 10 and adapted to be wound up on the other element; a rotary driver from which to rotate the latter element in the direction to wind said connection thereon (as its driver 32—33 or 35); a drive clutch (as 39 or 41, corresponding to 15 such driver) movable to intercouple the driver and said latter element for rotation together; a brake clutch movable to apply resistance to the first element (as 43 or 44 corresponding to 20 such element), and means (as the plate or slide 25 and the sleeves) movable to and from position (as from and to the, here, neutral position) to move the drive clutch to intercouple the driver and said latter element and during its own such movement (here both to and from said position) 25 engageable with the brake clutch to move the latter to apply braking resistance to the first-named element.

Having thus fully described my invention 30 what I claim is:

1. The herein-described method of treating fluid-pervious fabrics in succession which consists in winding a fabric to be treated and a fluid-pervious blanket together into a composite fabric-and-blanket mass, subjecting such mass 35 to steam, unwinding the fabric and blanket and winding the blanket independently of the fabric into a wound mass, and subjecting the latter mass to a vacuum, and repeating the foregoing steps as to each succeeding fabric to be treated. 40

2. The herein-described method of treating fluid-pervious fabrics in succession which consists in winding a fabric to be treated and a fluid-pervious blanket together into a composite fabric-and-blanket mass, subjecting such mass 45 to steam, unwinding the fabric and blanket and winding the blanket independently of the fabric into a wound mass, and subjecting the latter mass to a vacuum, and repeating the foregoing steps as to each succeeding fabric to be treated, maintaining the blanket mass subjected to the vacuum throughout substantially all of each period during which the blanket is wound with a fabric into a composite fabric-and-blanket mass. 50

3. The herein-described method of treating fluid-pervious fabrics in succession which consists in winding a fabric to be treated and a fluid-pervious blanket together into a composite fabric-and-blanket mass, subjecting such mass to steam, unwinding the fabric and blanket and winding the blanket independently of the fabric into a wound mass, and subjecting the latter mass while being formed to a vacuum, and repeating the foregoing steps as to each successive 55 fabric to be treated. 60

4. The herein-described method of treating fluid-pervious fabrics in succession which consists in winding a fabric to be treated and a fluid-pervious blanket together into a composite 70 fabric-and-blanket mass, subjecting such mass to steam, unwinding the fabric and blanket and winding the blanket independently of the fabric into a wound mass, and subjecting the latter mass to a vacuum and heat, and repeating the 75

foregoing steps as to each succeeding fabric to be treated.

5. The herein-described method of treating fluid-pervious fabrics in succession which consists in winding a fabric to be treated and a fluid-pervious blanket together into a composite fabric-and-blanket mass, subjecting such mass to steam, unwinding the fabric and blanket and winding the blanket independently of the fabric 10 into a wound mass, and subjecting the latter mass to a vacuum and heat, and repeating the foregoing steps as to each succeeding fabric to be treated, maintaining the blanket mass subjected to the vacuum and heat each time the

blanket is wound with a fabric into a composite fabric-and-blanket mass.

6. The herein-described method of treating fluid-pervious fabrics in succession which consists in winding a fabric to be treated and a fluid-pervious blanket together into a composite fabric-and-blanket mass, subjecting such mass to steam, unwinding the fabric and blanket and winding the blanket independently of the fabric into a wound mass, and subjecting the latter 10 mass while being formed to a vacuum and heat, and repeating the foregoing steps as to each successive fabric to be treated.

WILLIAM J. KOCH.
